UNITED STATES PATENT OFFICE

2,649,349

COMBINATION ARTICLE OF FURNITURE

Nathan Goodrich, Brooklyn, N. Y.

Application February 8, 1951, Serial No. 209,959

4 Claims. (Cl. 312—199)

1

This invention relates to a combination article of furniture in the form of a book case and folding table, or the like.

In apartments and other small living quarters, it is desirable to conserve space, therefore the use of a large dining room table, spare chairs and a book case in a small room would take up considerable space and unduly crowd the room, thus impairing the artistic room furnishings and comfort of the occupants of the room. It is therefore the primary object of this invention to provide a single article of furniture which may be normally folded into a relatively small compact unit to serve as a bookcase and a storage compartment for spare folding chairs, household utensils, table linen, etc., but which may be unfolded without disturbing the contents of the bookcase to provide either a single or double size table when a table for dining purposes, desk purposes, or the playing of card games is needed.

Another feature of the invention resides in a folding combination article of furniture which includes two separate articulated sections, normally arranged in compact back to back relation to conserve space but which sections may be swung to various angular positions and be transformed into one or a pair of separate tables about which persons may sit for dining or card playing purposes.

A further feature of the invention is the provision of a combination bookcase and a normally folded table which may be nested within a fireplace opening, or within the imitation fireplace opening of an imitation mantelpiece and fireplace, with the bookcase facing outward, thus conserving space in small living rooms where bookcases and tables would unduly crowd the same.

A still further feature of the invention is the provision of a combination bookcase and folding table which is easy to move around and set up for use as a table, and when set up, the same is strong and rigid to withstand the weight of dining service when used as a dining table.

A still further feature of the invention is to provide a combination article of furniture of the above mentioned kind which does not detract from the artistic furnishings of a room when in either normally folded position as a bookcase or in unfolded set up position for use as a table.

With these and other objects in view, the invention resides in the certain novel construction, combination and arrangement of parts, the essential features of which are hereinafter fully described in the following specification, are par-

2

ticularly pointed out in the appended claims and are illustrated in the accompanying drawings, in which:

Figure 1 is a front elevational view of the combination article of furniture in folded position and nested within the fireplace of an imitation mantelpiece.

Figure 2 is a perspective view of the combination article of furniture per se in folded position.

Figure 3 is an end elevational view.

Figure 4 is a vertical transverse sectional view.

Figure 5 is a top plan view showing the bookcase section and storage section in an extended position against a wall, in full lines, and in back-to-back relation in dotted lines.

Figure 6 is a fragmentary elevational view of one of the table tops in folded position with parts broken away.

Figure 7 is a front elevational view of one of the table tops in set up position.

Figure 8 is a side elevational view of one of the table tops in set up position.

Figure 9 is a detail vertical sectional view through the latch mechanism for securing the table top in folded position.

Figure 10 is a top plan view of the table top of both furniture sections in extended set up position.

Figure 11 is a top plan view showing the bookcase section against a wall and the other section swung to a position at right angle thereto with its table top in raised position.

Figure 12 is a top plan view of the two sections in V-shaped relation with the table tops in raised position.

Referring to the drawings by reference characters, the letter A designates my combination article of furniture in its entirety which broadly includes a rectangular shaped bookcase section B and a similar shaped complementary storage section C. The bookcase section B includes a rectangular frame embodying a flat horizontal bottom 10, upstanding end walls 11 and 12 and a flat horizontal top wall 13. A vertical partition wall 14 divides the bookcase section B into relatively narrow rear compartment 15 and a wider book compartment 16, the latter being provided with horizontal shelves 17 on which rows of books may be supported and displayed.

The storage section C is of the same size and shape as the bookcase section B but is of less depth and the same includes a horizontal bottom wall 18, vertical upstanding side walls 19—19 and a flat horizontal top wall 20. A vertical partition 21 divides the frame structure of the sec-

tion C into a front storage compartment 22 and a rear compartment 23. The front storage compartment 22 is normally closed by a pair of swinging doors 24-24 mounted on hinged pivots 25 whereby access to the interior of the storage compartment 22 may be had by the outward swinging of the doors 24.

Hinged to the bookcase section B at the rear lower edge of the top wall 13 as at 26, is a table top 27 which is of a width approximating the width of the bookcase section and of a length to extend from the plane of the underside of the top wall 13 to the plane of the underside of the bottom wall 19 when the table top 27 is in folded position as shown in Figure 4 of the drawing.

Hinged at 28 to the lower rear edge of the top wall 20 of the storage section C is a table top 29 similar in size and shape to the table top 27, and the outer free corners of the table tops 27 and 29 are beveled as at 30 for a purpose to be presently explained.

The sections A and B are swingably connected at one of their adjacent sides by means of pivoted links 31 arranged adjacent the top and bottom of the said sections as clearly shown in Figure 2. When the sections A and B are arranged in back to back, or front to front relation, the links 31 are fully countersunk in slots 32 provided in the end walls 11 and 19 of the respective sections. Beveled corners 30 of the table tops 27 and 29 facilitate the countersinking of the links 31 to avoid interference of the table top with the movement of the lower link.

Fixed to the rear of the partition wall 14 is a U-shaped bracket 32 having spaced ears 33 which are embraced by ears 34 of a tongue member 35, the ears of the tongue member and bracket being pivotally connected by a hinge pin 36, and carried by the hinge pin is a helical spring 37, one end of the spring abutting the bracket 32 and the other end bearing against the inner side of the tongue 35. The tongue 35 constantly bears against a wear plate 38 fixed to the underside of the table top 27. It will thus be seen that the pivoted tongue 35 is under the influence of the spring 37 which tends to urge the table top 27 outwardly and upwardly to an unfolded position, but suitable releasable latch means is provided for securing the table top 27 in the folded position shown in Figures 2, 3, 4 and 5 of the drawing.

A table top lifting mechanism similar to that just described is also provided for imparting an automatic lifting of the table top 29, to an open position, and it is not believed necessary to repeat the construction, other than to state that the bracket 32 of the spring actuated lifting mechanism for the table top 29 is fixed to the front of the partition wall 21 of the section C.

Releasable latch mechanisms are associated with the two sections B and C for holding the table tops 27 and 29 in folded position against the action of the spring actuated table top lifting mechanisms and it is believed that a description of one of the releasable latch mechanisms will suffice for the other. In view of the fact that in Figures 7 and 8, the table top 27 of the bookcase section B is shown in raised position and these views clearly illustrate the releasable latch mechanism and folding leg mechanism, these mechanisms as applied to this section B will be specifically described, but these same mechanisms are used in association with the table top 29 of the storage section B. Fixed to the partition 14 is a bracket 33' to which one end of a

releasable latch member 34' is pivoted as at 35', the said latch member being provided with a hook portion 36', the nose of the hook being rounded. Engageable with the hook portion 36' is a hook shaped keeper member 37' fixed to the underside of the table top 27. An expansion spring 38' acts upon the latch member 33' to hold the hook shaped portion 36' in engagement with the keeper 37', the rounded nose of the hook portion 36' permitting the latch member to be forced to a position to enable the fixed keeper member 37' to become engaged therewith. The latch member 34' is provided with a tail piece 39 which is engaged by a pedal 40, which pedal is hinged to the partition 14 as at 41. There is sufficient friction in the hinge joint 41 so that the pedal 40 is prevented from dropping under its own weight when the table top is in raised position. For the purpose of actuating the latch device 34' to effect its disengagement with the keeper 37', there is provided an actuating lever 42 pivoted intermediate its ends as at 43, one end of the lever extending through a slot 44 in the side walls 12 of the section B whereas the opposite end of the lever extends into the compartment 15 and has one end of a contractile spring 45 connected thereto, the other end of the spring fixed at an adjacent corner of the compartment. The inner end of the lever 42 is adapted to engage the pedal 40 due to the normal angle at which the pedal 40 is disposed, whereby depression of the pedal will cause it to press against the tail end 39 of the latch member 34' and move the hook portion 36' out of the path of the keeper 37', whereupon the spring actuated table top lifting device will swing the table top to raised position. After each actuation of the lever 42, the same returns to the position shown in Figure 7 and the spring 38' returns the latch member 34' to a position where it may again be engaged by the keeper 37' when the table top is swung to lowered position.

Fixed to the underside of the table tops 27 and 29 are folding legs and the legs of the two table tops being identical, a description of the legs connected to the table top 27 of the section B will suffice.

Fixed at opposite sides to the underside of the table top 27 are brackets 46, each bracket having end ears 47 which receive outwardly extending pintles 48 carried by the terminal ends of V-shaped tubular leg members 49. Pivoted at 50 to the outermost branches of the V-shaped leg members 49 are one end of links 51, the other end of the links having pins 52 which are slideable in slots 53 provided in brackets 54 fixed to the underside of the table top 27. The outer ends of the slots 53 are provided with downwardly extending offset portions 55 into which the pins 52 seat when the leg members 49 are in fully opened position. The leg members 49 are normally folded one within the other as illustrated in dotted lines in Figure 6, but as the table top is swung upwardly, the leg members drop to their unfolded position and eventually assume a vertical position as shown in Figure 7 and are held against folding by the seating of the pins 52 entering the offset notches 55.

For the purpose of preventing swinging of the sections B and C relative to each other when either in a back to back relation or when in reversed position for use of the article as a table, I provide a latch member 56 pivoted to the free end of the section C as at 57, the free end of the latch 56 being provided with notches 58 and 59

in opposite edges for individual engagement with a headed pin 60 extending outwardly from the side wall 12 of the section B. When the sections B and C are in back to back relation as shown in Figure 3, the notch 58 is engageable with the pin 60 but when the sections B and C are swung to a position wherein their normal fronts face each other as shown in Figure 10 of the drawing, the notch 59 of the latch is engaged with the pin 60.

When the two sections B and C are arranged in back to back relation as illustrated in Figures 2, 3, and 4 of the drawings, a removable filler strip 61 is inserted between the spaced inner sides of the top walls 13 and 20, said filler strip resting upon the inner ends of the down folded table tops 21 and 29.

Assume that the combination article of furniture A is in the folded position shown in Figures 1 to 4 inclusive, and that it is desired to transform the same into a double dining room table as illustrated in Figure 10. The combination article of furniture A is normally positioned with the section C against the wall or within a fireplace opening G of a combination mantelpiece and fireplace H as illustrated in Figure 1. To transform the article of furniture into a table, the article A is pulled outwardly into a room, the latch 56 is swung open, the filler piece 61 removed and the sections B and C are then swung relative to each other by means of link connections 31 and when swung entirely around, the sections are reversed relative to each other in order that the table top sides of the sections are disposed outwardly. The latch actuating levers 42 are depressed, thus releasing the table tops 21 and 29, whereupon the spring actuated tongues 35 swing the table top sections to a raised horizontal position coextensive with the flat horizontal top walls 13 and 20 of the sections B and C. As the table tops 21 and 29 move upwardly, the pivoted leg members 49 drop downwardly and eventually become locked by engagement of the pins 52 in the offset notches 55 at the outer ends of the brackets 54. When the two table tops 21 and 29 are fully raised, the combination article assumes the position shown in Figure 10, whereupon a full size dining room table is available for use.

The storage compartment 22 is adapted to receive folded chairs which may be removed from the compartment by opening of the doors 24, and the said chairs used for persons who are to be seated about the table.

To facilitate ease in swinging the sections B and C relative to each other, the bottoms of the same are provided with dome shaped feet 62 or with casters or other equivalent devices which will facilitate the easy sliding of the article of furniture over a floor or carpet.

When it is desired to fold down the table top sections, the pins 52 are lifted out of the notches 55, whereupon the legs are free to swing to a position flat against the underside of the table top, and the tops are then lowered against the tension of the spring actuated tongues 35 and the table tops eventually secured in a folded position by reason of the engagement of the keeper members 37' with the releasable latches 34'.

By reference to Figures 11 and 12 of the drawing, it will be noted that the combination article of furniture may be arranged in other forms than fully collapsed as shown in Figure 2, and fully opened for use as a dining room table as shown in Figure 10. In Figure 11 the bookcase section

B may be placed against the wall and the section C swung out to a position at right angle to the bookcase section with the table top 29 of the section C raised to provide a single table and which may remain in this position to provide a permanent table for the furnishing of a room. In Figure 12, the sections B and C are swung outwardly into a substantial V-formation with the table tops 21 and 29 unfolded to their raised position, thus providing two separate tables about which persons may sit for the playing of card games. Also, by reference to Figure 5, it will be seen that the two sections B and C may be swung to a position to face a wall and the table tops 21 and 29 may be swung to a raised open position for use as a desk or for individual table purposes.

Having described my invention, what I believe to be new is:

20. 1. A combination article of furniture comprising a pair of complementary sections, each having a top, a bottom and sides, with open front and back, and a transverse vertical partition therein between said front and back, a table top hinged at the back of each section and normally folded flat against said back each section having a space behind said partition adjacent its back then closed by said table top, said sections being normally arranged in back to back relation, link means swingably connecting said sections together at one side permitting said sections to be swung to front to front relation to facilitate the raising of the table tops, folding legs carried by said table tops for supporting the same in raised position
25. 35. when said sections are opened and disposed in said spaces when said tops are folded against said sections, and releasable latch means for securing said sections in closed back to back relation.
40. 2. A combination article of furniture comprising a pair of complementary sections arranged in normal back to back relation, each having a top, a bottom and sides, with open front and back, and a transverse vertical partition therein between said front and back, link means connecting said sections together at one end permitting the swinging of the same from a normal back to back relation to a front to front relation, table top sections hinged at the tops of the backs of said sections below the plane of the top thereof and normally folded flat thereagainst to face each other when said sections are in normal back to back relation, each section having a space behind said partition adjacent its back then closed by said table top, legs movably joined to the table tops for supporting said table tops when the table tops are set up and disposed in said spaces when the table tops are folded down against the sections, and a removable filler piece resting on the inner ends of said table top sections when folded to fill the space between the tops of said sections.
45. 60. 3. A folding article of furniture comprising in combination, a pair of furniture sections, each having a top, a bottom and sides, with open front and back, and a transverse vertical partition therein between said front and back, a table top hinged to be folded against the back of each furniture section at the top thereof, each section having a space behind said partition adjacent its back then closed by said table top, said sections being normally disposed in back to back relation, link means swingably connecting said sections together at one side and permitting said sections to be swung relative to each other to a reverse position in front to front relation to enable the table tops to be raised to table forming
55. 70. 75.

position, and means pivotally connected to said table tops for supporting the respective table tops in raised position when swung thereto, said means being disposed in said spaces when said table tops are folded against said sections.

4. A combination article of furniture comprising a pair of complementary sections normally arranged in back to back relation to form a bookcase or like article of furniture, each section having a top, bottom and sides, with open front and back, and a transverse vertical partition therein between said front and back, link means connecting said sections together at one end permitting the swinging of said sections to a reverse front to front relation, latch means for locking said sections in back to back relation, and table top extension leaves hinged to the respective sections at the backs thereof and normally folded flat thereagainst, each section having a space be-

hind said partition adjacent its back when closed by said table top, said table top extensions adapted to be swung to a horizontal position when said sections are in front to front relation whereby to form a table, and means pivotally connected to said leaves for supporting the sections in horizontal table forming position, and disposed in said spaces when said leaves are folded against the sections.
